CLAIM

The ornamental design for a beverage dispenser as shown and described.

DESCRIPTION

FIG. 1 is a perspective view of a beverage dispenser showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The broken lines shown in the drawings depict portions of the beverage dispenser that form no part of the claimed design.

The unshaded surfaces adjacent broken line edges form no part of the claimed design.
